UNITED STATES PATENT OFFICE.

REX W. HOVEY, OF ST. JOHN, NEW BRUNSWICK, CANADA.

PULP-WOOD DIGESTER.

Application filed January 21, 1928. Serial No. 248,429.

This invention relates to new and useful improvements in pulp wood digesters and particularly to the nozzle equipment for feeding or circulating the liquor there-
5 through. The object of the invention is to provide a nozzle or such like liquor conveying means which will be quickly and easily installed or repaired, without damaging or dismantling the parts of the digester in prox-
10 imity to said means.

Another object is to provide a nozzle connection in which the stresses exerted thereon will be transferred directly to the digester shell.

15 A further object is to provide a nozzle or pipe connection and gland therefor, which will resist the action of the liquor passing through the nozzle.

According to my invention I provide a
20 metallic sleeve which is secured to the lining of the digester. The sleeve has a threaded external surface projecting beyond the wall of the digester for receiving a nut and washer for sealing the opening in the shell.
25 The nozzle is removably held in the sleeve and suitable sealing means are provided to prevent the liquor from passing between the nozzle and the sleeve. The nozzle is extended and a collar is secured thereto.
30 Passing through the collar, or flange, are supporting studs which transfer any strain exerted directly to the digester shell. A pipe connection is secured to the collar by suitable bolts, and suitable reinforcing ribs are pro-
35 vided for strengthening the said connection.

In the drawings which illustrate my invention:—

Figure 1 is a sectional side elevation of a nozzle and gland therefor showing its connection to the digester shell.
40

Figure 2 is a sectional elevation taken on the line 2—2 Figure 1.

Figure 3 is a sectional side elevation taken on the line 3—3 Figure 1.

45 Referring more particularly to the drawings, 11 designates the outer metallic shell of a digester which is provided with a suitable lining 12, which will resist the action of the chemicals used in the manufacture of chemi-
50 cal wood pulp. The lining and shell are apertured as shown at 13 and mounted in said apertures and secured by ridge keys 14 is the sleeve 15. The sleeve is cemented, or otherwise secured to the lining. The sleeve 55 has an externally threaded portion 16 which projects beyond the outer face of the diges-

ter shell. To strengthen the shell around the aperture, a suitable pad 17 is riveted or otherwise secured thereto. The apertures in the shell and the pad are slightly larger in 60 diameter than the outside diameter of the projection. To seal this opening and prevent liquor from the digester from passing between said projection and the shell, a lead washer 18 surrounds the sleeve and is pressed 65 against the pad by means of a nut 19. A lead washer 19^a between the surface 38 and the inner surface of the shell is pressed, by movement of the nut 19, to seal the opening for the sleeve. The nozzle 20 is slidably mounted in 70 the sleeve and is provided with a flange 21, which cuts against the face 22 of the sleeve. A sealing ring 23 of lead, or such like material, is placed between the adjacent faces of 75 the flange and the sleeve. There is a space 26 between the sleeve and the outer wall of the nozzle. The outer wall of the nozzle is threaded and projects beyond the end of the sleeve and receives a nut 24. Between said nut and the end of the sleeve a soft metallic 80 washer 25 is placed to seal the space 26. The nut 24 draws the flange against the sleeve at its flanged end. A threaded collar or flange 27 is secured to the end 28 of the nozzle. The flange is directly supported on studs 29 85 extending outwardly from the reinforced portion of the digester shell. A double flanged pipe connection 30 is secured to the flange 27 by means of the bolts 31, which pass through said flange and the adjacent flange 90 32 of the pipe connection. Suitable ribs or fins 33 may extend between the flanges of the pipe connection to reinforce same. The reinforced connection may be secured to the pipes 34 and 35 of the liquor circulating, feed, 95 or discharge system. The free end 36 of the nozzle projects into the digester.

It will be readily understood that many modifications may be made to the general construction disclosed without departing from 100 the spirit of the invention.

In operation the sleeve is permanently secured to the wall of the digester and the nozzle is easily slipped into place and drawn tightly against the sleeve by means of the nut 105 on said sleeve. The washers which are of soft material are flattened out and, in spreading, seal the clearance spaces between the sleeve and the nozzle. The sleeve is drawn into place by a nut engaging with the wall 110 thereof and the soft metal washer is placed between the wall of the digester and the nut

to prevent liquor from passing through the aperture formed in the digester. The removable flange secured to the nozzle and to the reinforced section of the shell, ensures a rigid connection, so that any strains which would otherwise be placed on the nozzle are transferred directly to the shell through the bolts or studs. The pipe connection in proximity to the removable flange is reinforced so that there is no deflection therein and the strains are transferred to the flange and from thence to the digester shell. The nozzle is very easily removed for repairs and all parts in proximity to the nozzle are protected from the eating action of the acid. A cementitious filler 37 is placed between the lining and the flange formed integral with the nozzle. There is practically no strain on the nozzle and sleeve, so that the parts in contact with the shell are prevented from vibration, and once the nozzle is fitted thereto, no further adjustments need be made.

Having thus described my invention, what I claim is:—

- 25 1. In digester construction, a sleeve keyed to the lining of the digester and having a threaded portion projecting outwardly from the wall of the digester, a soft metallic washer surrounding the sleeve and a nut on the threaded portion for pressing the washer to seal the aperture in said wall around the sleeve.
- 30 2. In digester construction, a sleeve keyed to the lining of the digester, said sleeve having an externally threaded portion extending beyond the wall of the digester, a pipe pass-

ing through the sleeve, said pipe having a flange in proximity to the lining, adjustable metallic sealing means for closing the aperture surrounding the sleeve, and adjustable metallic sealing means at the end of the sleeve.

3. In digester construction, a sleeve keyed to the lining of the digester, said sleeve having an externally threaded portion, extending from the outer wall of the digester, a pipe 45 slidably mounted in the sleeve, said pipe having a flange at one end and a threaded portion at the other end, a soft metallic sealing member between the flange and the sleeve, a soft metallic washer surrounding the sleeve 50 and fitting against the digester shell, a nut on said sleeve for sealing the aperture surrounding the sleeve by pressing against the adjacent washer, a sealing ring at the end of the sleeve and surrounding the pipe, and a 55 nut on said pipe for drawing same into position.

4. In digester construction, a sleeve secured to the lining of the digester, a pipe flanged at one end slidably mounted in the sleeve, adjustable sealing means between the sleeve and the digester wall, adjustable sealing means surrounding the pipe at both ends of the sleeve, a flange adjustably secured to the pipe and means for transferring the load from 60 the flange to the wall of the digester.

5. A device according to claim 4, having stud connections between the adjustable flange and the digester wall.

In witness whereof, I have hereunto set 70 my hand.

REX W. HOVEY.
